United States Patent Office

Des. 177,686
Patented May 15, 1956

177,686

BICYCLE

Bernard Mennesson, Neuilly-sur-Seine, France, assignor
to Societe d'Appareils de Controle et d'Equipement des
Moteurs, S. A. C. E. M., Neuilly-sur-Seine, France, a
French society

Application July 15, 1955, Serial No. 36,988

Claims priority, application France February 18, 1955

Term of patent 14 years

(Cl. D90—8)

Fig. 2.

Figure 1 is a side view of a bicycle, showing my new design; and

Figure 2 is a fragmentary perspective view of a part of the frame of this bicycle.

The side opposite Figure 1 is substantially similar to that shown and the front and rear of the bicycle are of conventional configuration.

I claim:

The ornamental design for a bicycle, as shown and described.
